UNITED STATES PATENT OFFICE.

CHARLES HULTGREN, OF CHICAGO, ILLINOIS, ASSIGNOR TO S. KARPEN & BROS., A CORPORATION OF WEST VIRGINIA.

UPHOLSTERING-MACHINE.

1,247,403.

Specification of Letters Patent.

Patented Nov. 20, 1917.

Application filed January 19, 1917. Serial No. 143,241.

To all whom it may concern:

Be it known that I, CHARLES HULTGREN, a citizen of the United States, residing at Chicago, in the county of Cook and State 5 of Illinois, have invented a new and useful Upholstering-Machine, of which the following is a specification.

This invention relates to improvements in upholstering machines of the class invented and adapted for feeding the stuffing or filling into the case or cover of the up- 10 holstery.

The principal objects of the invention are to produce a simple and effective machine 15 for the purpose mentioned, but which is not only capable of accomplishing the usual results of facilitating the introduction of the stuffing or filling into the case or cover, but which is readily adjusted so as to operate 20 in connection with various sizes of stuffings or fillings, and which is especially adapted for operation upon and to prepare for introduction into the upholstering case or cover that class of stuffing or filling comprehend- 25 ing an internal coiled-spring construction, particularly of that type of coiled-spring construction made in accordance with the patents to James Marshall, No. 685,160, and No. 698,529, and others of 30 this type, and wherein it is usual and customary to surround the spring-construction thus formed with one or more layers of soft material, such, for instance, as cotton bat- 35 ting, and which, when located between the spring-construction and the case or cover of the upholstery, forms a soft interposed lining, rendering the completed article more comfortable as well as increasing its durability.

40 Various other objects, of more or less importance, will hereinafter appear, and the invention consists in various features of construction and combinations of parts hereinafter described and particularly appearing in the appended claims.

Referring to the drawings:

Figure 1 is a side elevation of an upholstering apparatus or machine typifying my invention, the same being shown in operation;

Fig. 2 is a top plan view of the same, while

Fig. 3 is a front elevation thereof;

Fig. 4 is a fragmentary view in horizontal section on the line 4—4 of Fig. 1; 55

Fig. 5 is a similar transverse vertical section on the line 5—5 of Fig. 1;

Fig. 6 is a horizontal section on the line 6—6 of Fig. 1; and

Fig. 7 is a detail in perspective of the fol- 60 lower.

Similar numerals of reference indicate similar parts throughout the drawings.

In producing the machine or apparatus, I employ a suitable stable frame-work or 65 base-structure, for example, as in the present instance, wherein there is comprised the pair of front and rear vertical uprights or posts 1 and 2, respectively, connected in pairs by upper and lower cross-sills 3 and 4, respectively, and longitudinally disposed upper and lower side-sills 5 and 6, respectively.

The two upper side-sills 5 support the outer edges of a longitudinally disposed horizontal feed-table 7, surmounted by vertical sides 8, relatively adjustable by some convenient means. In this instance, angular standards 9, are bolted to the sides 8, the lower horizontal portion of each standard 70 75 being slotted, as shown, to receive ordinary adjusting-bolts 10, provided with clamping-nuts. Through these mediums the sides 8 may be relatively adjusted to and from each other whereby the feed-table will be adapt- 80 85 ed to accommodate stuffings or fillings of various widths.

The feed-table 7 is preferably formed of two similar companion sections, each supported at its inner edge by a supplemental 90 sill 11, extending rearwardly beyond the frame, and these sections being spaced apart, produce, at their inner edges, an intermediate, longitudinally disposed, narrow channel 12. A metal strip 13, forms the 95 bottom of this channel.

Journaled in transversely alining bearings in the sills 11 and 5, near the front of the frame, is a feed-shaft 15, carrying a sprocket-wheel 16, running in the channel 100 12. A similar sprocket-wheel 18, runs in the rear end of the channel 12, and is mounted on a shaft 17, journaled in the rear ends of the sills 11.

Adapted to travel continuously in the channel 12 and supported by the metal bottom-plate 13 thereof, and engaging the teeth of the sprocket-wheels 16 and 18, the former of which is the drive-sprocket, is a sprocket feed-chain 19, the same being endless and therefore passing over and under the feed-table. At some suitable intermediate point, upon a short transverse shaft 10, supported in suitable bearings bolted to the undersides of the sills 11, is mounted an idle sprocket-wheel 21^a, the function of which is to support the underside of the sprocket-chain 19.

15 A clamp 21, surmounts the feed-table described, between the longitudinal sides 8 thereof, and, like said table, is preferably composed of two longitudinally disposed companion sections 22, each secured to the 20 underside of a pair of similarly disposed supporting-bars 23. Each of these sections, through the medium of its bars 23, is pivotally supported on a rear cross-rod 24, the ends of which enter vertical slots 25, formed 25 in the rear posts 2 above the feed-table. These posts are further provided with vertically disposed cross-slots 27, and in each of the latter is mounted a bored and threaded block 26. In suitable cavities formed in 30 the sides of these blocks rest the extremities of the cross-rod 24, and the threaded bores of the blocks are engaged by vertical adjusting-rods 28, the lower ends of the latter being threaded for the purpose. At the upper 35 per end of each of the adjusting-rods 28 is located a beveled pinion 29, and these operate in mesh with corresponding pinions 30, located on a transverse operating shaft 31, journaled in the upper ends of the posts 2, 40 and carrying at one end an operative means, in this instance a hand-wheel 32.

The sections composing the clamp 21, it will be understood, are at their rear ends, free to move laterally on the rod 24, and any 45 convenient means may be employed for retaining them when once adjusted to accord with the space between the sides 8 of the feed-table, as, for instance, the means illustrated. For this purpose, I may employ a 50 pair of transversely alining companion sleeves 32, mounting one upon each pair of the bars 23. In these sleeves may be located an adjusting-rod 33, threaded and carrying nuts 34, at opposite sides of each of the 55 sleeves. The nuts merely coact to retain the sleeves and rod in adjusted position in a manner that will at once be obvious.

A hollow vertical guide 35, may be secured to each of the posts 2, and above said 60 guides may be located sheaves or pulleys 36, while within each guide may be suspended by a cable 37, a counterbalancing-weight 38. The cables mentioned pass over the sheaves or pulleys, have their rear ends made fast 65 to the counterbalancing-weights, and their

front ends connected to the clamp 21, at some point near the free front end of the latter, in the present instance, the sleeves 32 being the points of connection. It will be understood that the combined weight of the 70 two counterbalancing-weights 38 about equal the weight of the clamp, so that the latter may be readily raised and lowered.

At the front of discharge-end of the feed-table, and forming a continuation thereof, is 75 a discharge-chute 39, designed to receive the unclosed end of the upholstering cover 40 (see dotted lines Fig. 1.) This chute is rectangular in cross-section and operates to hold the upholstering cover during the 80 process of inserting the stuffing or filling, as is usual in apparatuses of this character. Carrying out the idea of making the present machine adjustable for upholstery of various sizes, it becomes necessary to employ a 85 chute having the same characteristics, and this I accomplish by constructing the same of four right-angular sections of sheet-metal, 41. These four angular sections being assembled in such manner that each of 90 the upper sections overlaps its companion, and likewise with the lower sections, and at their sides the upper sections and lower sections also overlap, it will be seen the chute as a whole is capable of adjustment both 95 vertically and horizontally, and is thus capable of being adjusted in accordance with the feed-table and its auxiliaries, by which is meant the sides 8 and the clamp 21, so as to adapt it to receive upholstering covers of 100 various dimensions.

Each of the sections 41, of which the chute is composed, has a rear angularly disposed flange 42, the flanges of the upper pair of sections being upwardly disposed and those 105 of the lower sections being reversely or downwardly disposed. The flanges 42 of each transverse pair of sections 41 overlap, and those of the lower sections engaging the upper front cross-sill 3, and therefore being 110 stationary with the feed-table, while those of the upper sections engage a superimposed vertically adjustable cross-bar 43. This cross-bar 43 is, by means of adjusting-bolts 44, passing through the ends of the 115 same and into vertical slots 45, formed for this purpose in the front vertical posts 1, and through and beyond into vertical adjusting-blocks 46, adjustable vertically. These blocks are bored and threaded vertically and in such are threaded the lower ends of vertical adjusting-rods 47, (see detail Fig. 6.) The upper ends of the adjusting-rods 47, each carries a beveled pinion 48, which mesh with and are driven by companion pinions 49, fixed upon a transverse operating shaft 50, journaled in the upper 125 ends of the two front posts 1. For convenience of operation the end of this operating-shaft may be provided with a hand- 130

wheel 51. The adjusting-bar 43, may be longitudinally slotted, as at 52, and through the medium of adjusting-bolts 53, provided with suitable wing-nuts, and located in the 5 slot, and passed through openings in the flanges 42 of the upper sections 41 of the chute, lateral relative adjustment of the chute is provided for.

It will, of course, be understood, that the 10 apparatus described and illustrated may be operated in any desired manner. In the present instance, I have shown a conventional type of electric motor 54, for this purpose, the same being shown conveniently 15 mounted on a base 55, supported on the lower side-sills 6. An intermediate shaft 56, is journaled in bearings 57, also located on the sills 6, in advance of the motor, and upon this shaft mounted to rotate therewith, is a small spur-gear 58, and a drive-pulley 59, the latter being connected to the drive-pulley 60, of the motor, by a belt 61.

62 designates the clutch-shaft, journaled in advance of and slightly above the shaft 25 56, and at the front of the frame-work of the apparatus. At the outer end of this shaft is mounted to rotate therewith, a small spur-gear 63, and at an intermediate point, there is loosely mounted on the shaft, 30 a spur-gear 64, the hub of which forms one member of an ordinary friction-clutch 65. This clutch is operated in the usual manner by a vibratory lever 66, pivoted at its upper end, as at 67, to a suitable point of the 35 frame-work, the lower end of the lever being pivoted, as at 68, to a rocking-link 69, mounted on a swiveled treadle 70, carried by the lower front cross-sill 4. At an intermediate point, the lever 66, is pivoted, as at 40 71, to a conical sleeve 72, constituting the companion member of the clutch, so that, as will be evident, by a depression of the treadle by the foot of the operator, the lever 66 will be vibrated to the right, the clutch thrown to 45 operative position, and the shaft 62 rotated together with the spur-gear 63 carried thereby. When the foot of the operator is removed, a retracting coiled-spring 73, connected at one end to the rocking-link 69 and 50 at its other end to the adjacent post 1, serves to disconnect the clutch, so that the gear 64 runs idle. The shaft 15, carrying the front sprocket-wheel 16, extends beyond one of its 55 bearings, and carries a large spur-gear 74, which meshes with and is driven by the small spur-gear 63, of the shaft 62, when said latter shaft is rotated, and in this manner is motion transmitted from the motor 54, or other source of energy, to the driving 60 sprocket 16, and hence to the feed sprocket-chain of the apparatus.

75 designates a clamping-bar, located between the two front posts 1, and extending rearwardly so as to overlap and bear upon 65 the free end of the clamp 21. This clamp-

ing-bar is supported at its opposite ends at the upper ends of a pair of vertical draw-rods 76, the lower ends of which may be laterally disposed, as at 77, and connected loosely to a pair of opposite levers 78, each 70 of which is mounted at its rear end upon a transverse rod 79, situated under the sills 6. A coiled-spring 80, connected to one of these levers 78, at one end, and at its upper opposite end to the adjacent post 1, serves 75 to normally elevate the levers, and, consequently the clamping-bar. The companion lever is provided at its free end with a foot-pedal 81, by which rod 79 may be rocked against the tension of the spring 80. A 80 locking-pawl 82, is pivoted, as at 83, to the lever 78 carrying the pedal, and is designed to automatically engage with a rack-bar 84, fixed to the adjacent post 1. It will be evident that a depression of the treadle 81 will, 85 through the medium of the draw-rods clamp the clamping-bar down upon the free end of the clamp 21, and in this position the parts will become locked through the medium of the locking-pawl and rack-bar just described. By releasing the pawl from its engagement with the rack-bar, the spring 80 will re-elevate the clamping-bar out of its clamping position upon the clamp, so that the latter may be elevated to the position 95 shown by dotted lines in Fig. 1.

Referring more particularly to Fig. 7, I have illustrated a convenient form of follower well adapted to coact with the feed-board and feed sprocket-chain heretofore 100 described. This follower consists of a cross-head 85, designed to rest transversely upon the surface of the feed-table, and an angular shank 86, the front upturned end of the shank being secured, as at 87, to the rear 105 face of the cross-head. At its rear, the shank may be downwardly bent to form a hook 88, designed to removably engage with the links of the feed sprocket-chain 19. It will be evident that followers having various widths 110 of heads 85, may be provided, so that the width of the follower will coincide to some degree, at least, with the width of the upholstering being formed, and, therefore, with the width of the feed-table as adjusted. 115

If desired, also, the space between the sections 22, composing the swinging clamp, may be covered by a metal plate 89, the same being attached to the underside of one of the said sections 22 and slidably overlapping the 120 corresponding side of the companion section. (See Fig. 5.)

Where the lengths of sections or fillings permit, a series of them may be prepared at the rear end of the apparatus, the sections 125 being pushed forward in the feed of the machine as they are prepared for introduction into the upholstery covers through the discharge-chute at the front. To prevent buckling of the sections, the surface of the feed- 130

table may be waxed, and in order that each section may move squarely along by pressure brought against its rear end, I may and preferably do, employ spacing-boards 89, 5 the upholstering fillings and boards being indicated by dotted lines in Fig. 1. It will be seen as the fillings are prepared they are moved along by hand until the feed is filled, the spacing boards being inserted after each 10 filling. When a sufficient number of fillings have been prepared, the follower is placed on the feed-table in rear of the last filling of the series, the down turned end of the shank of the follower being engaged with a 15 convenient link of the sprocket-chain 19. The machine is then started, and by introducing the upholster covers successively at the front end of the discharge-chute, each has discharged or directed therein a filling, 20 after which it only remains to close the end of the cover in the usual manner. It will be understood, of course, that previous to starting the machine, the clamp 21 is lowered upon the fillings, and the clamping-bar 25 drawn down reasonably tight upon the free end of the clamp, the bar being capable of a slight swinging movement, forward and back, sufficient to permit the clamp to be raised and lowered. The fillings, especially 30 those of the spring construction heretofore referred to, are wrapped in one or more layers of cotton batting, the latter surrounding the bottom, top, ends and sides, and such may be accomplished in the feed-trough of 35 the machine. In this preparation it is simply necessary to lay cotton-batting in sufficient thickness and proportions in the bottom of the trough, leaving the ends of the length of batting over the sides, place the 40 upholster filling thereon, apply a top and end-layers, insert a filling or separating board 89, and move the filling thus prepared along a sufficient distance to permit of the preparation of the next filling, this operation 45 being continued until the feed-table is full, after which the follower is placed in position, the clamp lowered and locked in position, and the machine started and continued in operation until the supply of fillings have become exhausted. Of course, 50 where the upholstering to be formed is long, only one filling may be accommodated in the machine, in which case the spacing-boards will not be used, but simply the follower.

Having described my invention, what I claim, is:

1. In an apparatus of the class described, the combination with a frame-work, a feed-table having opposite sides located therein, a feed-chain located in the table, and means for operating said chain, of a clamp adapted to fit between the sides of the feed-table, means for pivoting the rear end of the clamp 60 to the rear end of the frame-work above the

table, means for simultaneously adjusting the pivots of said clamp, a clamping-bar arranged transverse the feed-table and above the clamp at the free end of the latter, draw-rods connected to the clamping-bar, levers pivoted to the frame-work and to the lower ends of the draw-rods, and means for locking said levers when depressed. 70

2. In an apparatus of the class described, the combination with a frame-work, a feed-table having opposite sides located therein, a feed-chain located in the table, and means for operating the chain, of a pivoted clamp adapted to fit within the space between the sides of the feed-table, links pivoted at their rear ends at opposite sides of the front of the frame-work, one of said links having a foot-treadle, vertically disposed rods pivoted at their lower ends to the free front ends of the links, a transverse clamp-bar connected at the upper ends of the rods and adapted to overlap and secure the front end of the clamp, a pawl carried by one of the links, a rack-bar adjacent to and adapted to be engaged by the pawl whereby to lock said rods in a depressed position, and a return spring for elevating said rods when released from the influence of the pawl. 80

3. In an apparatus of the class described, the combination with a feed-table formed in longitudinal sections the adjacent edges of which are spaced apart to form an intermediate channel, of a metal plate connected to the undersides of one of the sections and overlapping the other so as to form a smooth bottom for the channel, a feed-chain located in the channel and supported by the metal plate thereof, and means for operating the chain. 95

4. In an apparatus of the class described, the combination with a feed-table, an endless feed-chain located therein, and means for operating the latter, of relatively adjustable sides carried by the table, a superimposed clamp longitudinally divided to form sections adapted to fit between the sides, means for adjusting the sections laterally with relation to each other, and a metal plate secured in a stationary manner to one of the sections on its underside, extending across the opening between the sections, and overlapping and free to slide upon the underside of the opposite section to which it is secured. 110

5. In an apparatus of the class described, the combination with the frame-work comprising a pair of front vertical posts provided with vertical slots, bearing-blocks mounted in the slots, threaded shafts journaled in the posts and in the blocks, beveled gears at the upper ends of the shafts, a transverse operating-shaft journaled in the posts and provided with operating means, and beveled gears carried by said operating-shaft and meshing with those of the vertical shafts, of an upper transverse bar 125 130

connected to the bearing-blocks, a lower transverse bar fixed upon the posts, upper and lower pairs of right-angular sheet-metal sections flanged at their rear ends and respectively secured to the upper movable and lower fixed transverse bars, the meeting edges of said angular sections slidably overlapping, and a transversely and vertically adjustable feed leading to said angular sec-

tions and communicating with the discharge- 10 chute formed thereby.

In testimony whereof I have signed my name to this specification in the presence of two subscribing witnesses.

CHARLES HULTGREN.
